UNITED STATES PATENT OFFICE.

SAMUEL T. EHRLICH, OF NEWARK, NEW JERSEY, ASSIGNOR TO HUDSON TIRE CO., INC., OF NEWARK, NEW JERSEY, A CORPORATION OF NEW JERSEY.

DESIGN FOR A TIRE TREAD.

Application filed May 2, 1923. Serial No. 6,038. Term of patent 14 years.

To all whom it may concern:

Be it known that I, SAMUEL T. EHRLICH, a citizen of the United States, residing in the city of Newark, in the county of Essex and State of New Jersey, have invented a new, original, and ornamental Design for a Tire Tread, of which the following is a specification, reference being had to the accompanying drawings, forming a part thereof.

In the drawings,

Figure 1 represents, a plan view of an automobile tire, showing my new design.

Figure 2 represents, a transverse section of Figure 1, taken on line 2—2.

I claim:

The ornamental design for a tire tread, as shown.

SAMUEL T. EHRLICH.
